(57) CLAIM

The ornamental design for sunglasses towel clip, as shown.

DESCRIPTION

FIG. 1 is a front perspective view of sunglasses towel clip showing my new design;

FIG. 2 is a front elevational view thereof;

FIG. 3 is a top plan view thereof in an open position;

FIG. 4 is a top plan view thereof in a closed position; and,

FIG. 5 is a left side elevational view thereof.

The broken lines depict portions of the article that form no part of the claimed design.

1 Claim, 5 Drawing Sheets
